UNITED STATES PATENT OFFICE.

BENJAMIN D. BRINK, OF GRAND RAPIDS, MICHIGAN.

LOOSE-LEAF BINDER.

1,249,015.

Specification of Letters Patent.

Patented Dec. 4, 1917.

Application filed April 14, 1917. Serial No. 162,009.

To all whom it may concern:

Be it known that I, BENJAMIN D. BRINK, a citizen of the United States, residing at Grand Rapids, in the county of Kent and State of Michigan, have invented certain new and useful Improvements in Loose-Leaf Binders; and I do hereby declare the following to be a full, clear, and exact description of the invention, such as will enable others skilled in the art to which it app pertains to make and use the same.

This invention relates to binders for loose leaf records, and the primary object of the invention is to provide a binder of this type that is of such construction that the same will serve as a support for holding the bound leaves in a position where convenient access can be had to any of the leaves.

Another object of the invention is the provision of a binder and support of this type that will admit of the leaves being expeditiously filed or removed, as desired.

Other objects will appear and be better understood from that embodiment of my invention of which the following is a specification, reference being had to the accompanying drawings forming a part thereof, in which:

Figure 1 is a perspective view of a loose leaf record with the binder associated therewith,

Fig. 2 is a longitudinal sectional view taken through the loose leaf record, with the binder in supporting position and shown in vertical section,

Fig. 3 is a perspective view of the loose leaf record and binder with the top cover of the record in open position, and

Fig. 4 is a perspective view of the binder and the record with the binder in open position to admit of either the filing of additional leaves or the detachment of those that are filed.

Referring to the drawings in detail, the letter A designates a plurality of loose leaves that are interposed between companion pieces of card-board designated B. The leaves and card-board pieces are provided, at one end, and adjacent the longitudinal edges thereof, with registering openings C.

The combined binder and support comprise a pair of U-shaped elements 1 and 2, each of which has the free ends of the sides thereof offset laterally and curved, as shown at 3. The curved ends form sections

of looped members and the terminals of the curved ends of the elements 1 are pointed, as shown at 4, and normally received by recesses 5 in the terminals of the curved ends 6 of the element 2. The width of the element 1 is less than the width of the element 2 and the points of juncture between the sides of the element 1 and the offset upper ends 3 are flattened, as shown at 6, and lie in engagement with the inner sides of similar flattened surfaces 7 at the points of juncture between the sides and offset ends 3 of the element 2. Adjacent flat surfaces 6 and 7 have registering openings therein and a rod 8 lies between the flattened surfaces 6 on the sides of the element 1 and has the ends thereof loosely received by the openings in the respective adjacent flattened surfaces 6 and 7. A spiral spring 9 encircles the rod 8 and has one end extended around the adjacent offset portion 3 of the element 2 as shown at 10, and the other end of the spring extends around the adjacent offset end 3 of the element 1 as shown at 11. When the members 1 and 2 are moved in the direction of each other, the curved upper ends thereof will be moved in a direction away from each other, and the spring 9 will be tensioned so that upon release of the elements 1 and 2 the spring 9 will return them to normal position so that the opposed offset curved ends 3 of the elements 1 and 2 will coöperate to provide elliptical shaped loops, as shown more particularly in Fig. 2 of the drawings. When the curved upper ends 3 of the respective members 1 and 2 are separated, the curved ends can be passed through the openings in the leaves A and cover card-board pieces B, so as to bind the leaves and cover.

A hook 12 has one end loosely mounted on the lower cross bar of the U-shaped element 1 and when it is desired to file a large number of leaves, the members 1 and 2 are moved toward each other so as to separate the upper ends of the respective elements 1 and 2 and the bill portion of the hook 12 is then engaged around the cross bar of the U-shaped element 2, so as to prevent the spring 9 from returning the elements 1 and 2 to normal position during the filing operation. The lower connecting bars of the U-shaped elements 1 and 2 coöperate to provide a supporting base for holding the elements 1 and 2 in vertical position, as shown in the drawings, whereby the

bound leaves will be held in inclined position, so that the matter appearing on the uppermost leaf can be easily read. If desired, the binder can also be employed for 5 binding the leaves of a writing tablet; and supporting them in an inclined position, so that notes can be conveniently written thereon.

It is evident that various changes might 10 be resorted to in the form, construction and arrangement of the several parts without departing from the spirit and scope of the invention as claimed.

Having thus described my invention what 15 I claim as new, is:

1. A loose leaf binder comprising a pair 20 of vertically disposed and pivotally connected U-shaped elements having the free ends of the sides each curved in the direction of the adjacent ends, the said curved ends of the sides of the elements co-operating to provide loops adapted to be passed through openings in the leaves.

2. A loose leaf binder comprising a pair 25 of pivotally connected and relatively mov-

able U-shaped elements having opposed curved free ends co-operating to provide loops for reception by openings in the leaves.

3. A loose leaf binder including a pair of 30 relatively movable U-shaped elements having opposed curved ends normally lying in engagement with each other and co-operating to provide loops for engaging in openings in the leaves, the curved ends of the 35 respective elements being adapted to be separated upon movement of the elements in one direction and means carried by one of the elements and adapted to detachably engage the other element when the elements 40 are moved in the mentioned direction so as to prevent return of the elements to normal position.

In testimony whereof, I affix my signature in presence of two witnesses.

BENJAMIN D. BRINK.

Witnesses:
